WINDING REEL

Herbert C. Haller, R.D. 1, Hillsdale, N.Y.

Filed Dec. 12, 1961, Ser. No. 67,872

Term of patent 14 years

(Cl. D41—1)

FIG.1.

FIG.2.

FIG.3.

FIG. 1 is a top plan view of a winding reel showing my new design;

FIG. 2 is a side elevational view of the winding reel shown in FIG. 1; and

FIG. 3 is a perspective view of the winding reel in a position inverted from that shown in FIG. 1 and looking from above the same.

I claim:

The ornamental design for the winding reel, as shown.
